ARTICLE HOLDING DEVICE

George H. Myrick and Roy H. Bremer,
Rochester, Minn.

Application December 31, 1948, Serial No. 68,526

2 Claims. (Cl. 248—113)

1

This invention relates to article holding devices, more particularly to devices for supporting articles such as paint brushes, for example, on a wall of an open ended container, and the invention has for an object the provision of inexpensive, reliable and readily manipulatable holding devices of this character.

Various holding and supporting devices have heretofore been provided having a body portion including clamping means for supporting a paint brush or similar article within a container, and also including resilient clamping means adapted to be sprung over the edge portion of the open end of a paint can or similar container. Such holding devices are intended to support the paint brush in upright position within the container so that the bristle portion of the brush may be maintained in the paint or in oil or other liquid when not in use. The use of resilient clamping means for gripping the wall of the container involves the extra expense of spring steel or similar materials, which require tempering or other treatment after being formed, and which, due to fatigue after long periods of use, may become ineffective firmly to support the paint brush.

Accordingly it is a further object of this invention to provide an article holding device for paint brushes and the like which may be inexpensively formed from non-resilient materials.

Another object of the invention is the provision of an article holding device of this character which makes use of the resiliency of the container wall for insuring firm support of the holding device on the wall.

In carrying out the invention in one form, a holding device is provided for use with a container having a curved resilient wall and comprising a body portion having a pair of rigid wall engaging members extending from the body portion and spaced apart so as to respectively engage the inner and outer surfaces of the container wall when pressed over the top edge thereof, one of the members subtending an arc of the inner surface of the wall and the other of the members engaging the outer surface of the wall at a point within the subtended arc and being transversely spaced from the first member a distance less than the depth of the arc so as to effect distortion of the container wall, which thereby resiliently engages the rigid supporting members.

For a more complete understanding of the invention reference should now be had to the drawing in which:

Fig. 1 is a perspective view of an article hold-

ing device embodying the present invention, mounted on the wall of the container, which wall is shown only fragmentarily, and supporting a paint brush, which is shown in broken lines;

5 Fig. 2 is an end elevational view of the article holding device shown in Fig. 1, the showing of the container wall and the paint brush being omitted;

10 Fig. 3 is a top plan view of the article holding device, the showing of the paint brush being omitted; and

15 Fig. 4 is a sectional view on an enlarged scale taken through the rigid wall engaging members of the article holding device in order to illustrate the manner in which the can wall is distorted so as resiliently to engage the rigid member.

Referring now to the drawing, the invention is shown as embodied in an article holding device 10 comprising a rigid channel-shaped body portion 20 including opposed flanges 11 and 12 connected by a yoke portion 13. As shown, the flange 12 terminates in a return bend portion 14 which is extended to provide a spaced flange 15 which extends substantially parallel to the flange 12 to provide a channel 16 which is inverted with respect to the channel-shaped body portion. The flange 15, as shown, includes a portion 17 which extends downwardly below the yoke portion 13 of the channel-shaped body portion.

20 As shown in Fig. 1, the inverted channel 16, is adapted to be pressed over the open upper edge of a container, such for example as a paint can having a substantially cylindrical wall 18 formed of resilient material such as sheet metal. Although article holding devices embodying the invention are applicable to various types of containers; the container represented by the wall 18 in Fig. 1 constitutes the usual paint container in which, after the top has been cut away, the upper 25 rim of the wall 18 has been turned over to form a bead 19. The length of the flanges 12 and 15, with relation to the width of the channel 16 and the curvature of the wall 18 is such that when the channel 16 is forced over the upper edge thereof, the resilient wall 18 will be distorted so as resiliently to engage the flanges 12 and 15.

More specifically, and as best shown in Fig. 4, the length of the flange 12 is such that the arc of the container wall 18 subtended thereby when the channel 16 is pressed over the upper edge of the wall, is of a greater depth than the width of the channel. In other words the width of the channel 16 as represented by the letter "x" in Fig. 4, is less than the depth "y" of the arc 30 subtended by the flange 12. Accordingly when

55

the channel 16 is forced over the wall 18, the wall is distorted from its normal curvature, indicated by the broken lines in Fig. 4, to the solid line configuration illustrated, so that the wall resiliently engages the inner and outer flanges 12 and 15, at three spaced points firmly to support the article holding device 10 on the container wall.

Assembly of the device 10 on the container wall may be effected in various ways. For example, the body portion may be positioned on the upper edge of the wall 18, so that the depending portion 17 of the flange 15 engages the outer surface of the wall, and the flange 15 may then be pressed inwardly while at the same time exerting outward pressure on the wall 18 at the points represented by the arrows 20 in Figs. 3 and 4 so as to distort the wall 18 and permit the device 10 to be forced downwardly over the upper edge thereof to the position shown in Fig. 1. Alternatively, the device 10 may be tilted so that a portion of the wall 18 is caused to enter the channel 16 at one end thereof and the device 10 may then be forced downwardly so as to provide a cam action by the lower edge of the flange 12 and the flange 15 which distorts the wall 18 to the configuration shown in Figs. 3 and 4.

Although the flange 15 has been illustrated as being of substantially the same length as the inner flange 12, it will, of course, be understood that the flange 15 may be in the form of a narrow finger disposed intermediate the ends of the flange 12 and laterally spaced from the flange 12 a distance sufficient to provide the desired three point support while distorting the wall 18 so as to effect resilient engagement and firm support of the device 10. With the flange 15 formed as shown, however, the device 10 is reversible and may be applied to the wall 18 with the channel shaped body portion formed by the flanges 11 and 12 and the yoke portion 13 disposed either inwardly or outwardly of the container. In any event, however, the members 12 and 15 are rigidly formed so as to effect the desired distortion of the container wall 18.

In the embodiment of the invention shown, the inner flange 11 of the body portion of the device 10 terminates at its upper edge in an inwardly extending flange 21, which cooperates with the flange 11 to support suitable article engaging clamping means. Although any desired means may be employed, it is preferred to provide clamping means of the type comprising a continuous strip of spring material formed to provide opposed clamping fingers 22 and 23 connected at their spaced inner ends by a bowed yoke portion 24 which is adapted to be secured to the flange 11 by a suitable bolt 25 and a co-operating nut 26. The fingers 22 and 23 are adapted to resiliently grip and support the

handle 27 of a suitable paint brush 28 as indicated in broken lines in Fig. 1 and the gripping force exerted by the fingers 22 and 23 may be adjusted by tightening or loosening the bolt 25 as desired.

While a particular embodiment of the invention has been shown, it will be understood, of course, that the invention is not limited thereto since many modifications may be made and it is therefore contemplated by the appended claims to cover any such modifications as fall within the true spirit and scope of the invention.

What is claimed and desired to be secured by Letters Patent is:

1. A holder-device comprising a channel shaped rigid body portion, article holding means supported on one flange of said body portion, the other flange of said body portion terminating in a reversely extending flange spaced therefrom to provide a rigid channel inverted with respect to said body portion and adapted to be pressed over the edge of the open end of a container having a curved resilient wall, the width of said inverted channel being less than the depth of the arc subtended by the flange of said inverted channel engaging the inner surface of said container wall, whereby said container wall is distorted so as resiliently to grip said inverted channel.
2. A holder-device comprising a rigid body portion including a flange, article holding means supported on and extending from said body portion, said flange terminating in a reversely extending flange spaced therefrom to provide a rigid channel inverted with respect to said body portion and adapted to be pressed over the edge of the open end of a container having a curved resilient wall, the width of said inverted channel being less than the depth of the arc subtended by the flange of said inverted channel engaging the inner surface of said container wall, whereby said container wall is distorted so as resiliently to grip said inverted channel.
